UNITED STATES PATENT OFFICE.

ALBERT SCHMIDT, OF FLINT, MICHIGAN, ASSIGNEE TO CHAMPION IGNITION COMPANY,
OF FLINT, MICHIGAN, A CORPORATION OF MICHIGAN.

SPARK-PLUG.

1,283,572.

Specification of Letters Patent. Patented Nov. 5, 1918.

Application filed January 18, 1917. Serial No. 143,148.

To all whom it may concern:

Be it known that I, ALBERT SCHMIDT, a citizen of the Republic of France, residing at Flint, in the county of Genesee and State 5 of Michigan, have invented certain new and useful Improvements in Spark-Plugs, of which the following is a specification, reference being had therein to the accompanying drawings.

10 The invention relates to spark-plugs more particularly designed for use in high-speed internal combustion motors, and it is the object of the invention to provide for the more rapid dissipation of the heat from the 15 insulator. To this end the invention comprises, first, the means for maintaining molecular contact between the insulator and a body of relatively high heat conductivity; and further, various features of construction 20 as hereinafter set forth.

In the drawings:

Figure 1 is a longitudinal section through a spark-plug having its insulator provided with a heat conducting jacket molecularly 25 united thereto;

Fig. 2 is a similar view, showing a modified construction;

Fig. 3 is an enlarged section through the insulator and jacket.

30 In the construction of spark-plugs, electrical insulation can only be obtained where there is exposure of the insulator to the flame of combustion. On the other hand, such exposure results in the heating of the insulator, 35 and as the latter is usually a poor heat conductor difficulty is experienced in dissipating the heat with sufficient rapidity for high speed work. The slow rate of heat conduction is further due to the small amount of 40 contact between the insulator and the metallic casing, this being usually limited to a sealing gasket. With my improvement the heat conductivity of the insulator is greatly increased by covering a portion of its surface 45 with a metal or other high heat conducting substance which is in molecular contact with the insulating substance. This will provide a large contact area for conducting the heat from the insulating body 50 to the heat-conducting body, while the latter will convey the heat rapidly to the point of contact with the external case.

In detail and as shown particularly in Fig. 1, A is an insulator and B is a surrounding metallic jacket in molecular con-

tact therewith. The method of producing this molecular contact is preferably by electrolytic deposition, the surface of the insulator being first rendered conductive by the chemical or mechanical deposit thereon of a 60 thin film of conducting material, which is then coated electrolytically with a thick deposit of copper, silver or other metal high in heat conductivity. As shown in Fig. 1, the metallic jacket B surrounds the enlargement C of the porcelain, extending over the shoulder D which is seated against the gasket E on the shoulder F of the surrounding casing G. The parts are held in this position by a flange H on the casing G, which is 65 turned over an opposed shoulder I. With this construction the heat which is imparted to the porcelain through the exposed surface J will be conducted outward longitudinally and radially into the jacket B and 70 from the latter will pass by conduction to the gasket E and shoulder F to the casing G, which, being in contact with the water-cooled jacket, is at relatively low temperature. With the construction as illustrated 75 in Figs. 2 and 3, the insulator or porcelain A is formed with a tapering inner end K, and the metallic jacket B is carried over on to the tapering portion, as illustrated at B'. The outer surface of the jacket may then be 80 machined or otherwise fashioned to exactly fit a corresponding shape in the metallic casing G', so that the jacket forms not only the heat-conducting medium but also the bearing 85 or gasket which seals the insulator in the outer casing. This outer casing G' is formed with a corresponding taper, and the insulator is provided with a sufficient exposure of surface at its inner end to maintain electrical insulation. The insulator may be 90 retained in the casing by turning over the flange H' at the outer end in a similar manner to the construction shown in Fig. 1.

With the plug constructed as described, the rate of heat dissipation from the insulator is largely increased over any constructions heretofore devised, this being due primarily to the molecular contact of the insulator with the heat-conducting jacket and being further due in the construction shown 100 in Fig. 2 to the large contact between this jacket and the metallic casing. Consequently the plug may be used for high-speed work with little danger of a rise in temperature sufficient for preignition. 105

What I claim as my invention is:

1. A spark-plug, comprising an insulator and an electrolytically deposited coating on a portion of the surface of said insulator of material high in heat conductivity and in molecular contact with the insulator, and a casing in heat conducting contact with said coating.
2. In a spark-plug, an insulator, a metallic electrolytic deposit in molecular contact with a portion of the surface of said insulator and forming a body high in heat conductivity, and means for conducting the heat from said deposit to the casing of the plug.
3. In a spark-plug, the combination with the casing of an insulator, and a metallic electrolytically deposited coating in molecular contact with a portion of the surface of said insulator and in heat-conducting contact with said casing.
4. In a spark-plug, the combination with a casing of an insulator, an electrolytic metallic deposit on a portion of the surface of said insulator in molecular contact therewith, said deposit being of a metal high in heat conductivity, said deposit being in heat conducting contact with said casing.
5. In a spark-plug, the combination of an insulator having a central enlargement and a tapering portion therefrom to the inner end, of a surrounding jacket of electrolytically deposited metal extending over said enlargement and a portion of the taper of the insulator and being in molecular contact therewith, and a casing of corresponding form in contact with said jacket and clamped thereto.

In testimony whereof I affix my signature.

ALBERT SCHMIDT.
